A. PERRILLIAT.

EXCAVATOR.

APPLICATION FILED JULY 31, 1915.

1,279,149.

Patented Sept. 17, 1918.

UNITED STATES PATENT OFFICE.

ARSÈNE PERRILLIAT, OF NEW ORLEANS, LOUISIANA.

EXCAVATOR.

1,279,149.

Specification of Letters Patent. Patented Sept. 17, 1918.

Application filed July 31, 1915. Serial No. 42,857.

To all whom it may concern:

Be it known that I, ARSÈNE PERRILLIAT, a citizen of the United States, residing at New Orleans, Orleans parish, State of Louisiana, have invented certain new and useful Improvements in Excavators, the following being a full, clear, and exact disclosure of the one form of my invention which I at present deem preferable.

For a detailed description of the present form of my invention, reference may be had to the following specification and to the accompanying drawings, which illustrate my invention, wherein—

Figure 1 is an elevation of my apparatus; Fig. 2 is a plan thereof; Figs. 3 and 4 are longitudinal, and transverse sections of the skip; Fig. 5 shows a modified form of skip.

My invention is intended chiefly for building levees and embankments in cases where a wide and shallow borrow-pit is required beyond the transporting capacity of the ordinary excavator, which may be either a steam shovel, or a rotating-derrick excavator of the dragline, orange-peel or clam-shell type.

I purpose to use, in connection with such an excavator, mounted to travel or progress in a line parallel with the levee, a skip reciprocating transversely to the levee from the dumping point thereon to the delivery point of the excavator. Preferably I use two of these transversely-traveling skips and the load taken up by the excavator is delivered into the two alternately and by them is transported to the point of final delivery on the levee. In connection with this arrangement, I provide a special form of skip capable of being dumped from a distant point of control by inverting it and returning it to the loading point while still inverted.

The accompanying drawing illustrates the case where an existing levee is to be enlarged by additional material taken from a shallow borrow-pit of considerable width between the levee and the river. Such a levee is indicated at X at the left of Fig. 1 and it is assumed that the material is to be added on the right thereof to enlarge the levee to the form shown in the outline by dotted lines. The part marked B shows the material which is in process of being added to the levee and C indicates the borrow-pit from which the material is to be taken. On the existing levee is placed an engine D with

suitable winding drums operated thereby, it being my purpose to have the engine advance along the levee from time to time in the direction shown by the arrows R R as the work proceeds. Opposite the engine D in the direction of the river bank is shown an excavator of the boom type which may be a steam shovel or a derrick form of excavator having a bucket E which may be of the drag-line or orange-peel or clam-shell type. For illustration I have shown one of the dragline form. In any case the boom will be capable of rotating on a vertical axis around the base of the elevator and the bucket will be drawn out toward the end of the boom when loaded. It is manifest that an excavator of this kind is limited in its working area by the length of the boom which ordinarily is not more than one hundred feet in length and cannot practically be more than one hundred and fifty feet in length. It is the present plan of my invention to supplement the working range of the elevator A by combining with it a skip which will reciprocate back and forth in a direction transverse to the line of advance movement of the engine D which is in the direction indicated by the arrows R R, and the corresponding advance movement of the excavator, which is in the direction indicated by the arrows R¹ R¹. Such a skip is shown at F in each of the figures of the drawing and it is intended to be of considerable size—presenting, for instance, an opening ten feet square on its upper side in order that the bucket E may drop inside of it and deliver its load thereto. The skip is intended to slide on its bottom and for that purpose is provided on its under side with a smooth sliding surface with curved upturned ends H H as appears in Figs. 3, 4 and 5. It is open on its upper side and is provided with double side walls G G which are carried upward to form runners I I curved at each end, on which the skip may slide upside down on its return trip after being turned over and emptied. The bearing surface of the bottom is of much greater area than the bearing surface afforded by the runner I I, but the latter will only be used to carry the weight of the skip when it is empty, whereas, when it is loaded it will have the large bearing surface afforded by the curved bottom. The skip is to be drawn in a forward direction, when loaded, by a bridle H¹ attached to

the forward end of the skip at the points J J which are quite near the bottom, but it is also provided with a second draft attachment in the form of a similar bridle 5 L attached also to the forward end of the skip at the points K K which are just forward of the downwardly curved end of the runners I I. The curved ends of the runners coöperate with the bridle L to give the 10 rearward pull of the bridle a turning moment with respect to the bearing point of the skip on the ground in order that such backward pull of the bridle L (assuming that the bridle H¹ is relaxed) will invert or 15 overturn the skip endwise or longitudinally for dumping it. When it has been pulled back the required distance, the pull on bridle L will be relaxed and the skip turned over or righted by a reverse pull on bridle H¹ 20 and that reverse pull will be continued until the skip comes back to the loading point. In Fig. 5 a modified form of skip suitable for certain situations is shown which operates in the same way but is goose-shaped 25 in cross section, the forward end having an inverted arc-shaped projection U and the rear end having a similar but shorter projection T which, when the skip is being dumped, will tend to catch in the ground 30 and prevent a backward sliding movement of the skip. The form of skip shown in Fig. 3 may also be provided with a suitable spud at its rear to prevent backward sliding movement when it is being overturned and 35 dumped by the pull on bridle L.

Turning to Fig. 1, there is shown attached to the forward end of the draft bridle H¹ a cable M passing over the winding drum N on the platform of the engine D and a 40 draft rope P is also connected to the rearward bridle L and passes thence over the pulleys Q Q, which are anchored to the base of the excavator A and thence extend forward across the borrow-pit to the winding 45 drum O which is also on the base of the engine D. Thus the anchorage for the forward pull on the skip is on the engine bed whereas the anchorage for the rearward pull on the skip is at the base of the excavator 50 A. In Fig. 2 this arrangement is duplicated to provide two transversely-moving skips which return alternately to the delivery point of the excavator and are alternately filled by the excavator. This is to be used 55 in cases where the capacity of the excavator is greater than the transporting capacity of a single skip.

In operation this excavator will dig up the earth on its far side (away from the embankment) and also in its rear and the boom 60 will swing the material so dug up around

to the skip and dump it thereon. The skip will then transport the material across to the levee. A space of unbroken ground will be left ahead of the excavator for its forward 65 advance, which will, however, be removed in the rear of the excavator after it has passed by. In this way the excavator can remove all material in the area swept by its boom. When this has been done, the excavator, or 70 one following it, will make a second trip along a route parallel to the levee and midway between the levee and the previous excavation, the line of such previous excavation being defined by the delivery point 75 of the skip as shown on the drawing. On this second trip the material will be delivered directly to the levee by the excavator, it being understood that the strip of ground which has been left unbroken on the first 80 trip is of a width about equal to twice the length of the boom.

What I claim as new and desire to secure by Letters Patent is:

1. An invertible drag-skip comprising a 85 receptacle having a bottom bearing wall and load retaining walls surrounding same, a draft attachment near the bottom of the skip for dragging it forward when loaded, and a reverse draft attachment at a higher 90 point for inverting it to dump it by a pull thereon in the reverse direction.

2. An invertible drag-skip provided with 95 rolling surfaces and with a sliding under surface on which it bears when loaded and runners forming an upper sliding surface on which it bears when returning unloaded and which is of lesser area than the said under surface.

3. A drag-skip provided with a rolling 100 surface on which the skip may roll over endwise, its bottom portion being inclosed on four sides to retain the contents of the skip and its upper portion open to allow the contents to be discharged when the skip is rolled 105 over.

4. A drag-skip having a sliding under surface turned up at each end, and provided with a bottom portion which is inclosed on four sides to retain the contents of the skip, the upper portion being open to allow the contents to discharge when the skip is rolled over, a draft attachment for drawing it forward when loaded, and a second draft attachment at its upper and forward corner 115 with an out turned arc shaped upper surface with which the said second attachment coöperates to overturn the skip by a backward pull on said second attachment.

In witness whereof I have hereunto set my 120 hand this 23rd day of July, 1915.

ARSENE PERRILLIAT.
